UNITED STATES PATENT OFFICE.

VINCENT AJELLO, OF PITTSBURGH, PENNSYLVANIA.

CUE TIP.

Application filed March 20, 1925. Serial No. 16,998.

To all whom it may concern:

Be it known that I, VINCENT AJELLO, a citizen of the United States, and a resident of Pittsburgh, in the county of Allegheny and State of Pennsylvania, have invented a new and useful Improvement in Cue Tips; and I do hereby declare the following to be a full, clear, and exact description thereof.

My invention relates to tips for billiard cues and the like and to the manner in which they are secured to the cue stick.

One object of my invention is to provide a cue tip that may be more readily applied to or removed from a cue than those heretofore employed.

Another object of my invention is to provide a tip construction embodying means for strengthening the end of the cue to which the tip is applied.

Still another object of my invention is to simplify and improve generally cue tip structures.

One form which my invention may take is shown in the accompanying drawing wherein Fig. 1 is a view showing a portion of a cue to which my invention is applied; Fig. 2 is a longitudinal sectional view of a portion of the structure of Fig. 1; Fig. 3 is a similar view but showing the position assumed by certain of the parts during the act of removing from or affixing a tip to the cue; Fig. 4 is a detail view showing one of the parts entering into the structure of Fig. 2; Fig. 5 is a view looking in the direction of the arrows, on the line 5—5 of Fig. 3; Fig. 6 is a view taken on the line 5—5 but looking in the opposite direction and Fig. 7 is a detail view of another one of the parts entering into the structure of Fig. 2.

In practicing my invention I may provide a cue stick 7 of usual form that is of reduced diameter at its upper end, for the reception of a ferrule or sleeve 8 of ivory or similar material, to support and strengthen the outer end of the member 7. The stick 7 is cored on its longitudinal axis for a distance sufficient to receive a metal block 9 that may be driven into position therein and which has a knurled portion 10 to prevent turning thereof in its seat and to assist in preventing its accidental withdrawal from the stick 7. A plug 11 is provided for closing the lower end of the tubular portion of the block 9, such plug having a drive fit with said block. The plug is

provided with a socket or recess into which the lower flattened end of a threaded rod 12 loosely seats, so as to have longitudinal but non-rotative movement with respect to the plug 11.

A spring 13 surrounds the rod 12 and is held between the shoulder 12^a of the rod and a shoulder 14 in the block 9. In assembling the parts just referred to the spring is first placed upon the rod 12, the lower end of the rod is slipped into the plug 11, and then the whole inserted into the tubular portion of the block 9, the plug 11 having a drive fit with the block so as to be held against movement therein. The block 9 and its contained parts are then driven into the end of the stick 7.

The tip proper consists of leather or similar tip-forming material 15 and is glued to a base 16 of fibre or the like. Before applying the tip 15 to its base 16 a tubular pin 17 is inserted through the opening at the center of the base 16. This member 17 has a head that may be of angular form to hold it against rotative movement or may be held against such movement by the glue or cement that is employed for attaching the member 15 to the member 16. The member 17 is screw threaded on its interior wall so that it may be attached to the upper screw threaded end of the rod 12.

The block 9 is provided upon its upper enlarged end with a pair of teeth 18 that are adapted to sink into the fibre base washer 16 when the parts are in the position shown in Figs. 1 and 2, to prevent rotative movement of the tip 15 with respect to the stick 7.

In order to apply the tip 15 to the stick, it is first brought to the position shown in Fig. 3 and rotative movement imparted thereto to start the threaded member 17 upon the threads of the rod 12. An outward pull is then exerted on the tip 15 to move the rod 12 upwardly against the pressure of the spring 13 so that the tip and its seating washer 16 may be rotated without interference from the teeth 18 until it has been screwed in such distance that it will seat against the outer end of the ferrule 8. Upon release of the tip 15 the spring 13 will draw it inward so that the teeth 18 may be imbedded in the fibre washer 16. The tip is thus firmly held against rotative movement.

When it is desired to replace a worn tip

by a new tip, the old tip is grasped between the fingers and pulled outwardly so as to compress the spring 13 and permit the washer 16 to clear the teeth 18. The tip ⁵ then is rotated to unscrew it from the rod 12, and a new tip applied in the manner above described.

The block 9 is of such length that it extends into the stick 7 beyond the lower edge ¹⁰ of the ferrule 8 and strengthens the stick. Considerable loss has heretofore resulted from breakage of the sticks at the point where the lower end of the ferrules terminate. The metal member 9 prevents this loss ¹⁵ and also provides a firm seating surface for the washer 16.

I therefore provide a cue structure that is much stronger and more serviceable than those heretofore employed, and one wherein ²⁰ tip renewals may be made with a minimum expenditure of time, without impairment of its utility. The tip parts 15, 16 and 17 are made into a unitary structure and these units will be sold to billiard room proprietors and the like so that they can at all times keep their cues in good condition with a small expenditure of time and expense, since the cost of the units so constructed is small compared to the time lost in repairing ²⁵ cues by the old method wherein the cues were out of service during the period required for the glue to dry. It has heretofore been necessary for a billiard room proprietor to carry a large stock of cues on hand ³⁰ in order that he would have a sufficient number in condition for service while others were being repaired.

I claim as my invention:

1. The combination with a cue stick, of ⁴⁰ tip structure comprising a threaded member secured to the stick, means for yieldably holding said member against longitudinal movement, a tip, and a threaded member

secured to the tip and adapted to engage with the first-named threaded member. ⁴⁵

2. The combination with a cue stick, of tip structure comprising a threaded member secured to the stick, a tip, a threaded member secured to the tip and adapted to engage with the first-named threaded member, ⁵⁰ means for yieldably holding one of said threaded members against axial movement, and means for locking said tip and said stick against relative rotative movement.

3. The combination with a cue stick, of a ⁵⁵ centrally apertured metallic bushing secured to the outer end of said stick, a member disposed in said aperture and threaded at its outer end, means for preventing rotative movement of said threaded member ⁶⁰ within said aperture, means for yieldably holding said threaded member against axial movement, a tip, and a screw threaded member carried by said tip for engagement with the first-named screw threaded member. ⁶⁵

4. The combination with a cue stick, of a centrally apertured bushing having a reduced shank portion extending into said stick at the longitudinal axis thereof and having a shouldered head portion seating ⁷⁰ against the outer end of said stick, a threaded member within said apertured bushing, means for preventing rotative movement of said threaded member, means for yieldably holding said threaded member against movement in an axial direction, a tip, a screw threaded member carried by said tip for engagement with the first-named screw threaded member, and toothed projections upon the outer end of said bushing to prevent rotative movement of the tip when said tip is ⁷⁵ in operative position.

In testimony whereof I, the said VINCENT AJELLO have hereunto set my hand.

VINCENT AJELLO.
